**AUTOMATIC GUIDE VANE LOCKING DEVICE
FOR A HYDRAULIC MACHINE**

Charles F. Ambroz, Milwaukee, Wis., assignor to Allis-Chalmers Manufacturing Company, Milwaukee, Wis.

Filed Apr. 3, 1958, Ser. No. 726,237

5 Claims. (Cl. 253—122)

The present invention relates generally to improvements in hydraulic turbines and specifically to a hydraulic turbine having improved means for locking the guide vanes in the closed position.

Heretofore in hydraulic turbines automatic guide vane locking mechanisms have been constructed in various ways. One prior art construction consisted of a spring actuated latch engaging the operating ring of the guide vane operating mechanism when the guide vanes were in the closed position. Another type of guide vane locking mechanism incorporated the use of a hooked pawl to engage the guide vane operating rod when the operating rod was in the closed position.

The increased use of automatic guide vane locking devices on large hydraulic turbines presents engineering problems in the automatic guide vane locking devices heretofore used. The automatic guide vane locking device consisting of a pawl tripped by pressure from a fluid servomotor and spring biased into a locking position on the guide vane ring became impractical as turbines increased in size because of the distance between the fluid servomotor actuating the guide vane operating mechanism and the pawl to automatically actuate the locking device. As turbines increased in size and capacity the water pressure on the guide vanes and the fluid pressure of the servomotor, which operates the guide vane mechanism, either singly or in combination placed an eccentric load upon the guide vane operating rod, and the hook pawl type of automatic guide vane locking mechanism became inadequate because the forces exerted on the guide vane operating rod tended to bend the guide vane operating rod away from the hook pawl unless the rod was made larger than a convenient size and of material of great strength.

In the present invention it is proposed to provide automatic guide vane locking means which will engage the guide vane operating rod from two sides keeping the load of the forces on the rod symmetrical and engaging the operating rod in a manner which positively prevents the guide vanes from opening accidentally as by a failure of the guide vane operating mechanism.

In a preferred embodiment of the present invention, the guide vane locking action is accomplished by providing a pair of pawls with diametrically opposite pivot points about a rod of the guide vane adjusting means. Pawl actuating means are provided to move the pawls convergingly toward or divergingly away from the guide vane operating rod and thereby into and out of engagement with an adjustable detent means on the operating rod. The pawl actuating means are able to pivot the pawls convergingly toward each other and the shaft which is between the pawls so that the pawls simultaneously engage diametrically opposed portions of detent means when the guide vane operating rod is in the guide vane closed position to prevent movement of the guide vane operating rod in a guide vane opening direction. The pawls are pivoted away from the shaft to disengage the detent means

2

on the shaft and release the shaft for guide vane opening movement in response to operation of turbine starting means. Pawl disengaging action operates a switch that in turn operates a control device that actuates an operating mechanism for vane opening action of the vane adjusting means. Thus the pawls must first disengage before any vane opening action can take place. Furthermore, the pawls are biased to engage the detent means on the shaft and it is only by the positive operation of the turbine starting means that the pawls are released. Thus if for example, as in the preferred arrangement that will be described, the guide vanes are operated by a fluid pressure operated servomotor, a failure of the fluid pressure supply system will not make it possible for the guide vanes to open accidentally.

It is therefore an object of this invention to provide in a hydraulic turbine improved automatic guide vane locking means which positively lock the guide vanes in the closed position.

Another object of this invention is to provide in a hydraulic turbine automatic guide vane locking means which simultaneously place a symmetrical load on the guide vane operating rod.

Another object of the invention is to provide in a hydraulic turbine improved automatic guide vane locking means which will insure that the guide vanes must be positively and intentionally unlocked before any vane opening action can take place.

Another object of the invention is to provide in a hydraulic turbine improved automatic guide vane locking means which will insure that no vane opening action can be initiated until pawls that lock the vanes have been disengaged so that it is not possible for the vane operating servomotor to place a load on the pawls when the pawls are in vane locking position.

Other objects will appear hereinafter as a description of the invention proceeds. The novel features of the invention and how the objects are attained will appear more fully from this specification and the accompanying drawings showing an embodiment of the invention and forming a part of this application and all of these novel features are intended to be pointed out in the appended claims.

In the drawings:

Fig. 1 is a fragmentary plan view of a portion of a hydraulic turbine with portions of the covering structure cut away to show parts of a guide vane adjusting mechanism and their relationship to each other;

Fig. 2 is a plan view of a portion of the vane actuating mechanism partly in section; and

Fig. 3 is a side view of the structure shown in Fig. 2.

In Fig. 1 a portion of a hydraulic turbine 1 is shown as having adjustable vanes 2 for controlling the flow of water through the turbine. Vane adjusting means are shown, including an axially movable shaft 3 pivotally connected to guide vane operating ring 4. Guide vane operating ring 4 has a plurality of flanges 5 connected by guide vane links 6 to lever 7 which in turn is connected to movable spindle 8 of adjustable guide vanes 2. The axially movable shaft 3 is actuated by operating means shown as a servomotor 9 which in turn is actuated by a conventional speed governor (not shown). When the speed governor (not shown) calls for a change in the position of the adjustable guide vanes 2, servomotor 9 actuates shaft 3 which rotates guide vane adjusting ring 4, and guide vanes operating ring 4 through flanges 5 will move guide vane links 6 to rotate levers 7, spindles 8, and guide vanes 2.

Servomotor 9 has a piston 10 and a piston rod 11 which is connected to the shaft 3. Fluid pressure conduits 12 and 12a having ports 13 and 14 are shown connected to servomotor 9. Control means, shown in Fig. 3

as a solenoid operated control valve 35, are provided to control the admission of fluid pressure to the vane opening side of piston 10 for reasons that will be pointed out as this description proceeds. Detent means are shown in Fig. 1 as being a threaded nut 15 and a threaded gate lock bearing plate 16. Threaded nut 15 and threaded gate lock bearing plate 16 are adjustable on a threaded portion 17 of axially movable shaft 3. Threaded guide vane lock bearing plate 16 acts as a lock nut on threaded adjustable nut 15 to secure it in a preselected position. Pawl means shown in Fig. 1 as a pair of pawls 18 arranged respectively on opposite sides of axially movable shaft 3 are supported by shaft 19 shown in Fig. 2 as being connected to rocker arms 20. Rocker arms 20 are connected to pivot pawls 18 about the axis of shafts 19. The axis of each of the shafts 19 is perpendicular to axially movable shaft 3.

Fig. 1 further shows a member 21 fixed to servomotor 9 and arranged to engage threaded nut 15 at a preselected position on the shaft 3 when axially movable shaft 3 moves in a closing direction thereby limiting the vane closing movement of the axially movable shaft 3. The limiting of the closing movement of shaft 3 prevents injurious pressure from being placed on the engaging edges of guide vanes 2 when in the closed position. Rocker arms 20 shown in Fig. 2 are biased toward each other by spring 22 to rotate rocker arms 20 and shafts 19 and pawls 18 so that pawls 18 pivot convergingly toward each other and toward axially movable plate 3 to engage with threaded guide vane lock bearing plate 16 when said axially movable shaft 3 is in a vane closed position. A second biasing means consisting of a second fluid servomotor 23, piston 24 and piston rod 25, is connected to rocker arms 20 by link 26 connected to piston rod 25 and links 27 pivotally connected at one end to link 26 and at the other end to rocker arms 20. In Fig. 3 second servomotor 23 is shown as having fluid pressure inlet conduit 30 and exhaust conduit 31. Conduit 30 is connected to a fluid pressure source (not shown) and will admit fluid pressure to servomotor 23 when the turbine is to be started by actuating reversible solenoid valve 33. When piston rod 25 reaches the position furthest toward rocker arms 20, it will trip means shown in Fig. 2 as a limit switch 34 connected to a solenoid operated control valve 35 permitting fluid pressure to be admitted to the vane opening side of servomotor 9, thereby delaying the application of fluid pressure to the vane opening side of the piston 10 so that servomotor 23 will disengage pawls 18 from detent plate 16 before pressure can be admitted to servomotor 9 to begin moving the vanes in an opening direction.

The operation of the mechanism will be described beginning with the position shown in Fig. 1 wherein the vanes 2 are closed and the detent nut 15 and plate 16 are locked in position between the pawls 18 and the member 21. When the hydraulic turbine is to be started, solenoid valve 33 is actuated and fluid passes through conduit 30 shown in Fig. 3 to second servomotor 23. Piston 24 and piston rod 25 will move to the furthest position axially toward rocker arms 20. Links 26 and 27 coat with piston 24 and piston rod 25 to which link 26 is connected while they are moving to the position furthest axially toward rocker arms 20 and pivot rocker arms 20 in opposite directions, causing shafts 19 to rotate in opposite directions and pawls 18 to pivot about shaft 19 divergingly away from each other and out of contact with plate 16. After the pawls 18 are moved out of engagement with plate 16 piston rod 25, in its furthest position axially toward rocker arms 20, will trip limit switch 34 actuating solenoid control valve 35 to release fluid pressure through conduit 12 to the vane opening side of piston 10 to bias piston 10 in the vane opening direction. When piston 10 moves in vane opening direction piston rod 11 and shaft 3 move in the vane opening direction causing guide vane ring 4

and flanges 5 connected to guide vane operating ring 4 to move in a counterclockwise direction. Guide vane link 6 connected to flanges 5 and lever 7 connected to guide vane ring 4 are moved by the counterclockwise rotation of guide vane operating ring 4 causing spindles 8 to rotate and move vanes 2 to the open position.

When piston 24 of the second servomotor 23 has moved to its furthest position toward rocker arm 20 and for any reason the turbine must be shut down or an emergency failure occurs the fluid pressure is drained from the second servomotor 23 through conduit 30 by a reversal of solenoid valve 33. Conduit 31 appears for the purpose of draining off leakage past piston 24 of second servomotor 23. Spring 22 will bias rocker arms 20 in a direction opposite to the direction of their disengaging movement causing shafts 19 to rotate in a direction opposite to the direction of their disengaging movement and causing pawls 18 to pivot convergingly toward each other about shafts 19.

When the speed governor or an emergency shutdown calls for the vanes to move to the closed position, fluid pressure is admitted through fluid pressure conduit 12a and port 13 shown in Fig. 1 to the guide vane closing side of piston 10 and fluid pressure is drained from the vane opening side of piston 10 through conduit 12 causing piston 10 to bias piston rod 11 and guide vane operating rod 3 in the closing direction. Pawls 18 are in the closed position and ride up and over nut 15 and plate 16 and snap into position against threaded guide vane lock bearing plate surface 36 when the vanes are closed thus preventing any movement of axially movable shaft 3 in the opening direction. At the same time, surface 37 of adjustable threaded nut 15 engages member 21 preventing further movement of axially movable shaft 3 in the guide vane closing direction and preventing excessive forces from being applied to the engaging edges of guide vanes 2. Axially movable shaft 3 when moving in the guide vane closing direction rotates guide vane operating ring 4 in the clockwise direction, also rotating flanges 5 connected to guide vane operating ring 4 in the clockwise direction. Guide vane links 6 and levers 7 connected to flanges 5 rotate spindle 8 and guide vane 2 to the closed position.

Because the pawls 18 will not move divergingly away from each other and out of engagement with the plate 16 except when second servomotor 23 is biased by fluid pressure, the vanes will not be opened accidentally as a result of a failure of the fluid pressure system. Furthermore, no vane opening action can be initiated until the pawls have been disengaged so that it is not possible for the vane operating servomotor 9 to place a load on the pawls 18 when the pawls are in a vane locking position. And still further, the arrangement insures that the pawls 18 will engage and disengage the detent plate 16 simultaneously so that forces on shafts 11 and 3 will be balanced and no bending of the shafts will take place.

These and other features and advantages will be obvious to those skilled in this art. It will be obvious to those skilled in this art that the illustrated embodiment of the invention provides a new and improved guide vane locking means for locking the guide vanes in the closed position and accordingly accomplishes the objects of the invention. On the other hand it will also be obvious to those skilled in the art that the illustrated embodiment of the invention may be variously changed and modified or features thereof singly or collectively embodied in other arrangements other than that illustrated, without departing from the spirit of the invention or sacrificing all of the advantages thereof, and that accordingly the disclosure herein is illustrative only and the invention is not limited thereto.

What is claimed is:

1. In a hydraulic turbine, adjustable vanes connected to said turbine for controlling the flow of water through said turbine, vane adjusting means connected to said

vanes, first operating means connected to said adjusting means for moving said vanes between an open and a closed position, control means connected to said first operating means, said control means being operative to activate said first operating means, pawl means pivotally connected to said first operating means, biasing means connected to said pawl means and biasing said pawl means to pivot to engage with said vane adjusting means and prevent vane opening motion of said vane adjusting means, second operating means connected to said pawl means operative to overcome said biasing means and pivot said pawl means to disengage said pawl means from said vane adjusting means, and switch means connected to said control means and said switch means positioned to engage said second operating means when said second operating means acts to disengage said pawl means, said switch means being operative upon engagement with said second operating means to energize said control means to activate said first operating means.

2. In a hydraulic turbine, adjustable vanes connected to said turbine for controlling the flow of water through said turbine, vane adjusting means including an axially movable shaft connected to said vanes, first operating means connected to said shaft for moving said shaft to move said vanes between an open and a closed position, control means connected to said first operating means, said control means being operative to activate said operating means, a pair of pawls arranged respectively on opposite sides of said shaft, means connected to said first operating means for supporting each of said pawls for pivotal movement about an axis perpendicular to said shaft, biasing means connected to said pawls, said pawls being biased to pivot convergently toward each other and said shaft to engage with said shaft to stop vane opening motion of said shaft, second operating means connected to said pawls and operative to overcome said biasing means and pivot said pawls divergently away from each other and said shaft to disengage said pawls from said shaft, and switch means connected to said control means and said switch means positioned to engage said second operating means when said second operating means acts to disengage said pawl means, said switch means being operative upon engagement with said second operating means to energize said control means to activate said first operating means.

3. In a hydraulic turbine, adjustable vanes connected to said turbine for controlling the flow of water through said turbine, vane adjusting means including an axially movable shaft connected to said vanes, a first fluid pressure operated servomotor having a piston connected to said shaft to move said vanes in an opening direction when fluid pressure is delivered to one side of said piston and to move said vanes in a closing direction when fluid pressure is delivered to the other side of said piston, a pair of pawls arranged respectively on opposite sides of said shaft, means connected to said first fluid pressure operated servomotor supporting each of said pawls for pivotal movement about an axis perpendicular to said shaft, biasing means connected to said pawls, said pawls being biased to pivot convergently toward each other and said shaft to engage with said shaft to stop vane opening motion of said shaft when said shaft is in a vane closed position, a second fluid pressure operated servomotor having a piston assembly connected to said pawls and operative when fluid pressure is delivered to said second servomotor piston to overcome said biasing means and pivot said pawls divergently away from each other and said shaft to disengage said pawls from said shaft, fluid pressure conduit means connected to both of said servomotors, a control valve connected to said first servomotor to admit operating fluid to said first servomotor, and a limit switch connected to said control valve and said limit switch positioned to engage said piston assembly of said second servomotor upon pawl disengaging action of said second servomotor, said limit switch being

operative upon engagement with said piston assembly to operate said control valve to admit fluid pressure to said vane opening side of said first servomotor piston.

4. In a hydraulic turbine, adjustable vanes connected to said turbine for controlling the flow of water through said turbine, vane adjusting means including an axially movable shaft connected to said vanes, a first fluid pressure operated servomotor having a piston connected to said shaft to move said vanes in an opening direction when fluid pressure is delivered to one side of said piston and to move said vanes in a closing direction when fluid pressure is delivered to the other side of said piston, a pair of pawls arranged respectively on opposite sides of said shaft, means connected to said first fluid pressure operated servomotor supporting each of said pawls for pivotal movement about an axis perpendicular to said shaft, biasing means interconnecting said pawls, said pawls being biased to pivot convergently toward each other and said shaft to engage with said shaft to stop vane opening motion of said shaft when said shaft is in a vane closed position, a second fluid pressure operated servomotor having a piston assembly connected to said pawls and operative when fluid pressure is delivered to said second servomotor piston to overcome said biasing means and pivot said pawls divergently away from each other and said shaft to disengage said pawls from said shaft, first fluid pressure conduit means connected to said first servomotor including a solenoid operated control valve connected to said first servomotor to admit operating fluid to said vane opening side of said first servomotor piston, and a limit switch connected to said solenoid operated control valve, said limit switch being positioned to engage said piston assembly of said second servomotor after pawl disengaging action of said second servomotor, said limit switch being operative upon engagement with said piston assembly to energize said solenoid operated control valve to admit fluid pressure to said vane opening side of said first servomotor piston.

5. In a hydraulic turbine, adjustable vanes connected to said turbine for controlling the flow of water through said turbine, vane adjusting means including an axially movable shaft connected to said vanes, a first fluid pressure operated servomotor having a piston connected to said shaft to move said vanes in an opening direction when fluid pressure is delivered to one side of said piston and to move said vanes in a closing direction when fluid pressure is delivered to the other side of said piston, detent means mounted on said shaft and adjustably positioned along the axis of said shaft, a member mounted on said first fluid pressure operated servomotor and arranged to engage said adjustable detent means when said shaft moves in said vane closing direction to a preselected position to adjustably limit vane closing movement of said shaft, a pair of pawls arranged respectively on opposite sides of said shaft, means connected to first fluid pressure operated servomotor supporting each of said pawls for pivoting about an axis perpendicular to said shaft, a biasing spring connecting said pawls to bias said pawls to pivot convergently toward each other and said shaft to engage with said detent means to stop vane opening motion of said shaft when said shaft is in a vane closed position, a second fluid pressure operated servomotor having a piston assembly connected to said pawls and operative when fluid pressure is delivered to said second servomotor piston to overcome said biasing means and pivot said pawls divergently away from each other and said shaft to disengage said pawls from said detent means, fluid pressure conduit means connected to said first servomotor including a solenoid operated control valve connected to said first servomotor to admit operating fluid to said vane opening side of said first servomotor piston, second fluid pressure conduit means connected to said second servomotor to move said second servomotor piston to disengage said pawls, and a limit switch connected to said solenoid operated control valve, said

limit switch being positioned to engage said second servomotor piston assembly after pawl disengaging action of said second servomotor, said limit switch being operative upon engagement with said piston assembly to energize said solenoid operated control valve to admit fluid pressure to said vane opening side of said first servomotor piston.
